UNITED STATES PATENT OFFICE.

L. CLAYTON ERWIN, OF YORK, PENNSYLVANIA, ASSIGNOR OF ONE-HALF TO
CHARLES P. YOUNG AND JOHN H. THOMAS, BOTH OF SAME PLACE.

HARNESS.

SPECIFICATION forming part of Letters Patent No. 369,282, dated August 30, 1887.

Application filed June 30, 1887. Serial No. 243,006. (No model.)

To all whom it may concern:

Be it known that I, L. CLAYTON ERWIN, a citizen of the United States, residing at York, in the county of York and State of Pennsylvania, have invented certain new and useful Improvements in Harness, of which the following is a specification, reference being had therein to the accompanying drawings.

This invention relates to certain novel improvements in combined horse-detachers and shaft-loops, which improvements will be fully understood from the following description and claims, taken in connection with the annexed drawings, in which—

15 Figure 1 is a side elevation of my improved device as it appears when clasped upon a vehicle-shaft. Fig. 2 is a vertical section taken centrally through the device when clasped upon a vehicle-shaft. Fig. 3 is a side view of 20 the same parts, showing the same unclasped and in a condition to free themselves from the shafts. Fig. 4 is a side view of the flanged sliding collar which receives through it the shaft.

25 Referring to the annexed drawings by letter, A designates one of the shafts or thills of a vehicle.

I will here remark that my improved safety unhitching device will in practice be applied 30 to each one of the vehicle-shafts, which latter may be made in the usual manner.

On the shaft A, at a suitable place, are coiled springs b b, which are confined between collars a a, or their equivalents, rigidly secured to said 35 shaft and the ends of a cylindrical flanged collar, H, which is allowed to slide endwise on the shaft, restrained only by the coiled springs b b.

C designates a clasp, parts of which are adapted to embrace the collar H, between the 40 flanges thereof, as shown in Fig. 2. This clasp

consists, essentially, of two parts hinged together at f. One part is composed of the semi-circular embracing portion c², having a loop, c³, for the attachment of the belly-band strap. 45 From this part rises vertically a tongue, c, flanged at h h, and having formed on its upper end a loop, c⁴, for the attachment of the back-band strap. The face of this tongue c is preferably depressed, and in this depression 50 is secured a spring, s, for a purpose hereinafter explained. I also form on this tongue c two

horizontal branches, G G, having loops on their ends, to one of which is secured a hame-strap, J, and to the other a holdback-strap, J'. The other part, C', of said clasp consists of a semi-circular portion having a tongue-extension, C², adapted to lie snugly between the flanges h h on the edges of the tongue c, and to be braced by these flanges when the clasp is locked, as shown in Figs. 1 and 2. Between the two 60 flanges h h, and secured at one end in a recess formed in the tongue c, is a spring, s, the free end of which will press outwardly against the tongue C² when this tongue and a locking-slide, D, are in the positions indicated in full lines, 65 Figs. 1 and 2 of the annexed drawings.

D designates a locking-slide consisting of a horizontal embracing-loop, e, and a vertical tongue, e'. This device D is designed to slide on the tongues c C² of the clasp and to securely 70 hold them together and prevent a casual detachment of the clasp from the sliding collar H on the shaft A. Figs. 1 and 3 show the locking-slide D embracing and holding the tongues together, and Fig. 2 shows the said 75 slide D raised free from the tongue C² of the hinged part C' of the clasp. The slide D is then raised by means of a pull-cord, E, which may pass through a pulley-eye, g, fixed to the face of the tongue c near its upper end, and is 80 carried back and fastened in a convenient position to be manipulated by the driver in the vehicle.

Should it become necessary to quickly unhitch the horse from the vehicle in case of accident, the driver pulls on the cord E and raises the locking-slide D free from the tongue C², simultaneously with which the spring s will throw off laterally this tongue and allow the clasp to free itself from the collar H on the 90 shaft A.

It will be observed that the collar H is located between two springs on the shaft, thereby allowing a free elastic action of draft and backward thrust to said slide, and preventing undue shocks and concussion to the horse and vehicle. It will also be observed that by my invention I provide a cheap and efficient device whereby the use of singletrees and traces are obviated entirely, and which allows the 100 animal to be quickly detached from the vehicle should it become unmanageable.

Having thus fully described my invention, what I claim as new, and desire to secure by Letters Patent, is—

1. The combination of the vehicle-shaft, the flanged collar H on the same, the springs b, arranged on each side of the collar, the hinged clasp C, embracing the collar, the two hinged portions of the said clasp being provided, respectively, with tongues C' and c, the locking-slide D, embracing the tongues of the clasp, and the operating-cord E, attached to the said locking-slide, substantially as described.
2. In a horse-detacher, the combination of a hinged clasp consisting of the semicircular

portions hinged together and provided, respectively, with a long and short tongue, the loops G G' and flanges h h on the tongue c, the flanged collar H, adapted to be received loosely on an angle between springs, the spring s on tongue c, and a locking-slide, D, adapted to retain the clasp closed, substantially as described. 15

In testimony whereof I affix my signature in presence of two witnesses.

L. CLAYTON ERWIN.
